BUILDING WITH AIR SUPPORTED ROOF AND
METHOD OF CONSTRUCTING THE SAME

Herbert H. Stevens, Jr., Bantam, Conn.

Application November 26, 1942, Serial No. 466,982

12 Claims. (Cl. 108—1)

My invention relates to building structures supported by air pressure and the method of building the same.

In general, embodiments of my invention comprise a peripheral support, a membrane of substantially impermeable material serving as a roof element, means for anchoring the periphery of such membrane with respect to the peripheral support, and means for creating within the enclosure formed by such peripheral support and such membrane and the ground or floor or other bottom surface suitable increase of pressure of the air or other gas within such enclosure to thereby support such membrane in raised position.

Annealed low-carbon steel is preferred as the membrane roof element for reasons of structural and functional advantages, namely, that such steel is impermeable, i. e. precludes substantial air leakage, is available on the market in sheet form of great lengths, readily and effectively autogenously connectable at the lateral edges of such sheets to form varied dimensions of the roof, and possessing other attributes advantageous in attaining the objects of the invention.

The peripheral support may be of any suitable material such as concrete which may be molded to suitable configuration for affording suitable anchorage per se or in conjunction with the earth for the roof membrane.

Anchoring of the periphery of the roof membrane with respect to the peripheral support may be carried out in any suitable manner. Desirably, steel or the like, in suitable form such as forged shapes, plates, perforated sheets and the like may serve as the anchoring material, which may itself be anchored within the concrete during the molding stage. Auxiliary anchoring means may also be employed such as guy wires or the like suitably secured to the anchoring means or directly with the roof membrane or both.

Suitable means such as ducts or equivalent connected with the outlets of one or more air compressing means such as blowers exterior or interior, but preferably exterior, of the building structure and discharging within the enclosure formed within the building structure serve to increase the pressure of the air within such enclosure whereby the roof is raised and supported. Such air may be conditioned, namely, to remove dust and other foreign matter, also controlled in temperature and otherwise pursuant to conventional practice.

Desirably, such air or other gas is preferably inducted through ducts extending below the peripheral support and leading through the floor and delivering in the proximity of the floor, thus creating a free or conditioned air zone within the zone of operation of the operators or workmen or other occupants of the building structure.

Advantageously, air is exhausted from the enclosure or interior through the medium of towers enclosing exhaust ducts which connect with outgoing ducts leading through the floor and extending below the peripheral support to the exterior of the building structure. If desired, such self-exhausted air may be employed to drive an air turbine which may be connected with respect to the air blower, thus reducing the power costs of air supply.

In structures embodying my invention, the earth, i. e. ground, serves as an advantageous bottom, upon which flooring of desired character may be installed.

Structures embodying my invention may be constructed on beaches to extend over the water, applicable for enclosed shipyards, docks for submarines or the like, or hangars for seaplanes or the like, etc. The peripheral support of concrete or the like may be located wholly within the water, the water serving as the floor.

An advantageous method of building embodiments of my invention is carried out as follows:

Assuming an earth—or ground—type of structure to be erected, the earth or ground of the location for the structure is leveled off to approximate uniformity. About such leveled earth or ground, the peripheral support, say of concrete, is formed in molds located in trenches or cleared ground surrounding such leveled earth or ground. The leveled ground intermediate the wholly or partly constructed peripheral wall serves as a temporary support for laying thereupon the steel sheets, i. e. the roof membrane material, which are connected sheet to sheet at their contiguous lateral edges by seam-welding or other autogenous connection, or by soldering or equivalent. The ends of the thus connected steel sheets are then secured to the anchorages in turn secured to the peripheral wall. This procedure is continued until the whole of the necessary steel sheets are connected to one another to complete the roof membrane, including shaping the periphery of the roof material to conform to that of the peripheral support, and anchored relative to the peripheral wall. Air under pressure is then introduced within the enclosure of the build-

ing structure to elevate the roof membrane. The earth is removed to the desired level of the floor, preferably utilizing the portion of the earth interiorly adjacent of the peripheral wall for shoring purposes.

The steel or other roof membrane is desirably covered exteriorly with suitable roofing material such as asphalt, sheet roofing compositions, etc. for protection against corrosion and the like. Preferably, a heat reflecting medium is incorporated on the underside of the roof structure to reduce heat radiation into the interior of the structure.

The peripheral configuration of the concrete or other peripheral support may be circular or non-circular. A circular or equivalent configuration is advantageous in that such configuration is self-bracing in support of the roof. Earth may be employed to interiorly shore the concrete or other peripheral wall in joint support of the roof structure; earth may also be employed to exteriorly brace the peripheral support against elastic instability failure.

A factory constructed pursuant to the invention, adaptable to present day requirements, is typified by a structure of circular form, say twelve hundred feet in diameter which covers a clear span of approximately twenty-six acres. Say 18 gauge of say soft-deep-drawing steel, which is procurable in strips of ninety inches in width and six hundred feet in length may be employed as the roof membrane. The ends of the seam-welded steel sheets may be anchored to a steel plate, in turn secured to reinforcing rods buried in the concrete anchor ring. The exterior face of the steel sheets may be covered with one inch insulating board, applied with hot asphalt, upon which may be exteriorly applied, say, three-ply 20 year roofing.

Assuming an increase of air pressure of but two and one-half ounces per square inch above atmospheric pressure, such roof assumes a dome formation, which may be designed to have an advantageous height at its center of say sixty feet. Such increase in air pressure is negligible to the occupants in that it represents merely the difference in air pressure between the top and bottom floors of a sixty story building. The initial stretch of the steel sheet for such two and one-half ounces per square inch increased interior pressure is approximately one percent, well within the safe maximum stretch of approximately twenty percent of such type of steel. Increase of pressure of the interior air effects an elevation of the roof; however, the less the radius of curvature of the roof, the greater is its resistance against air pressure, wherefore, in the circumstance of any tendency of the roof membrane to bulge, as at any weaker or softer sections, and consequent reduction of radius of curvature of such bulged section, the greater is the resistance of such bulged section to bulge further.

With time the initial softening heat-treatment wears off, and the metal may be farther stretched and thus cold work-hardened to improve its tensile qualities. In the circumstance of unbalanced loads upon the roof membrane, as when covered by drifted snow, or sudden rain storm, the air pressure of the interior may be increased to overcome the weight of the snow drifts or water, without much danger of rupture of the unloaded roof membrane. Upon elevation of the roof, say by an increase of two and one-half ounce per square inch air pressure, maintenance of the roof in elevated status is readily effected at a con-

tinued increase of air pressure of approximately one ounce per square inch, an increase of air pressure corresponding approximately to the difference in air pressure between the top and bottom floors of a twelve story building. Rippling of the roof membrane due to excessive wind, is precluded or reduced to safe limits by reason of the damping effect of the continuously applied air pressure upon the interior face of the roof. The dome formation of the roof is advantageous in resisting internal pressure, and likewise resisting any suction or counterpressure arising by reason of external pressure differential caused by high winds, explosions, etc.

15 The above-referred to and other advantages are afforded, pursuant to the invention, by the employment of ductile material of the nature as above set out, serving as the prime membrane of the roof and by anchoring the same substantially completely about its periphery, whereby upon 20 subjecting the roof material interiorly of the building structure to relatively increased air pressure, the roof material is subjected at substantially all portions thereof to stretching forces 25 creating tensile stresses within the roof membrane in all directions substantially parallel to the surface of the roof membrane. Thus under wind condition of, say, gale velocity from any direction, or pressures varying in wide range, the 30 tensile stresses mutually perpendicularly within the roof material serve to dampen any fluttering initiated in any portion of the roof material.

35 In the circumstance of an explosion exteriorly of the building structure or even within the building structure, or by a gust of wind or any other suddenly applied load to a portion of the membrane, the tensile stresses within the roof membrane by virtue of excess pressure above that necessary in support of the roof serve to distribute 40 such applied forces throughout the membrane and aid in transferring such energy to the air adjacent to the membrane wherein it will be mainly dissipated. The tensions existing throughout the roof membrane serve also to spread concentrated loads over wider areas, enhance the 45 capability of the roof membrane to withstand such concentrated loads, and prevent the forces created by such applied concentrated loads from setting up damaging vibrations in or flutter of the 50 roof membrane.

The advantages gained by subjecting the ductile material of the roof membrane to stretching forces are enhanced by the dome configuration resulting from the membrane being anchored peripherally to the vertically extending substantially rigid peripheral walls, and particularly in enhancing the damping effect of the roof membrane to forces created by such applied loads.

55 Such factory structure may be supplied normally with the one ounce of air by, say, sixteen fans, forcing air into a system of concrete ducts beneath the floor, which have outlets in the floor, say, at thirty feet spacing. Four exhaust towers each of, say, forty feet height may serve to collect the heated air which rises from men, machinery, lights and other sources and carry the same down through the floor through ducts disposed below the concrete peripheral wall.

60 Danger of complete collapse is more a psychological problem than an actual one. Any single ventilating fan is sufficient to maintain the required increase of air pressure, as the assumed one ounce per square inch. The remainder of

the fans are used for ventilation. The provision of exhaust towers, indicated above, is sufficient to support the roof in the event of collapse of the air-supplying system.

A factory having the structure typified above, results in the saving of nine-tenths of the steel required in conventional construction. Such factory is easily and rapidly built and possesses low overhead and upkeep costs. The factory is readily camouflaged, highly resistant to bomb blasts, and particularly suitable for twenty-four hour per day black-out operation.

Embodiments of the invention are particularly adapted to be erected in locations such as deserts, viz. the Sahara Desert, or in jungles and other locations in torrid climates, in Iceland and other polar locations, requiring merely steel or other sheets of suitable roof membrane material and in certain instances Portland or equivalent cements to be transported from the United States or other industrial centers, and accordingly a minimum of transported building materials.

The use of a reflecting ceiling prevents thermal radiation downwardly, thus rendering the structure of especial utility for locations all over the globe, inclusive of the torrid zone and the polar zones. The exhaust air from the hotter strata in the upper zones of the interior may be utilized by suitable heat exchange means to preheat or add heat to the inflowing air in locations of low temperature and during the seasons of low temperature, thus reducing the cost of temperature regulation within the zones of operation of the occupants of the building.

Power may be obtained from the expansion of the air heated within the interior, by waste heat of men, lights and machinery and other sources and/or by sunlight on the roof or through a specially designed roof, transparent to solar radiation.

Power may also be obtained by suitable manipulation from external temperature changes and/or barometric variations.

Entry from the exterior into the interior, and correspondingly in exit, is afforded for persons by means of revolving doors or equivalent; for the entry of airplanes, trucks and the like, such door arrangement may be of the air lock type. Entry and exit of a train of cars may be accomplished by a single door. The opening of a door affording direct communication of the exterior atmosphere with the interior for a period of time requisite for the entry or exit of a train, truck or the like, effects a leakage of air pressure which is relatively inconsequential; the leakage effect of a hole in the roof construction caused, say by a bomb, perhaps of twenty foot diameter, is readily compensated to maintain any desired increased air pressure, say, one ounce per square inch within the enclosure, by an increased air delivery by the normal fan system, and by the employment of an auxiliary fan system, until the hole has been repaired or the air-leakage cause cured.

Further features and objects of the invention will be more fully understood from the following detail description and the accompanying drawings, in which

Fig. 1 is a vertical sectional view of one preferred embodiment of the invention.

Fig. 2 is a plan view of Fig. 1.

Fig. 13 is a detail vertical section of a portion of a structure typified in Fig. 1, illustrating one manner of anchoring the roof membrane with respect to the peripheral wall support.

Fig. 14 is a detail sectional view on line 14—14 of Fig. 13.

Fig. 15 is a detail vertical section of a portion of a structure generally corresponding to that of Fig. 13 but showing another embodiment.

Fig. 16 is a detail sectional view corresponding to that of Fig. 13 but showing another construction.

Fig. 17 is a detail vertical section through the roof, illustrating a preferred arrangement of materials.

Fig. 18 is a detail vertical section through the roof, illustrating another preferred arrangement of materials.

Fig. 19 is a detail vertical section through the roof, illustrating another preferred arrangement of materials.

Referring to the drawings, illustrating preferred embodiments of the invention, 50 indicates generally the roof, and 51 the peripheral wall support to which the periphery of the membrane of the roof 50 is secured. The earth or ground is indicated at 52.

As shown generally in Fig. 1 and in greater detail and enlarged in Figs. 7, 13, 15 and 16, the peripheral wall support 51 may be formed within the earth or ground 52; advantageously, the peripheral wall 51 is of concrete formed by pouring the concrete mix within suitable forms, properly located within a trench, indicated at 52a in Figs. 7, 13, 15 and 16, the earth or ground inwardly of the building structure, being preferably retained when it is desired to shore the peripheral wall in support of the roof 50. In certain types of constructions embodying my invention, the earth at the locations indicated generally at 52b, exteriorly of the building structure,

75 may also be retained for counter-shoring and

other purposes, referred to more fully hereinafter.

As indicated generally in Fig. 7, the air under pressure introduced within the interior 54 of the building structure may be supplied by suitable ducts, such as indicated at 55, furnished by one or more air compressors indicated generally at 56. Such ducts desirably extend below the peripheral wall support 51 and may be spaced mutually with respect to one another, usually uniformly about the periphery of the building structure. As indicated in Figs. 2 and 4, there may be a plurality, say, nine stations, each furnished with its own air compressor 56 connected at its outlet with a main air-supply duct 55, each such air-supplying duct preferably leading to distribution air-supplying ducts 57, see Figs. 7, 8 and 9, discharging through outlets 58 located in the floor 53 of the structure.

The exhaust of the air, see Fig. 1, is preferably effected by means of one or more towers 59 provided with ducts, the inlets of which are located within zones of relatively higher temperatures of the interior of the building structure, advantageously above the zones of operation of the operators or other occupants of the building structure. The ducts of such towers 59 communicate at the bottoms thereof with air outgoing ducts 60. See Figs. 8 and 9, which extend under the peripheral wall 51 to the exterior of the building. As indicated in Fig. 4, four such exhaust towers 59 have been found desirable. If desired, the air out-going ducts 60 may be located in close adjacency with respect to the air-ingoing ducts 55, as by placing each outgoing duct 60 side by side and intermediate two incoming ducts 55, indicated generally in Fig. 4 and in enlarged detail in Fig. 5. Such arrangement is advantageous in minimizing the amount of earth required to be removed in forming the troughs in the earth or ground in which the respective ducts are located; also, in affording the utilization of an air turbine motor, such as indicated at 61 in Fig. 5, through which the outgoing air is passed to drive the same as a motor in geared relation with one or both of a pair of air compressors 56, 56, as indicated in Fig. 5, supplying the compressed air, thus reducing the power for driving the air blowers 56, 56, referred to more fully hereinafter. Such side-by-side relationship of a heated air outgoing duct and an air ingoing duct is advantageous when it is desired to effect thermal interchange of the concerned air flows, described more fully hereinafter.

The peripheral edges of the roof membrane are anchored with respect to the peripheral wall by any suitable means. One such approved anchorage is indicated in Figs. 13 and 14, showing the roof membrane 61 seam-welded at its longitudinal, i. e., peripheral edges to a suitable anchoring member such as a bar indicated at 62, say, of cast steel, or a heavy plate or the like of suitable material, itself anchored within the upper portion of the peripheral wall 51, as by molding the same within the concrete peripheral wall, such anchoring member 62 may be also supplemented by suitable reinforcing elements such as steel wire indicated generally at 63, and/or perforated sheets of metal or the like, also molded within the concrete, and connected at its upper edge portions with such anchoring member 62, or directed to the membrane 61. Such supplemental anchoring means 63 may have an arcuate configuration, as indicated in Fig. 13 for strain stabilizing advantages.

In Fig. 16, the roof membrane 61 is shown seam-welded at its peripheral edges to a bar, plate or like anchoring member 64, in turn seam-welded or otherwise rigidly connected to wire, or perforated sheets, etc. indicated at 65, molded or otherwise rigidly lodged within the concrete or other peripheral wall 51; such anchoring means 65 may be lodged within the peripheral wall to extend downwardly and terminating arcuately at its lower end, as indicated in Fig. 16.

The configuration of the peripheral wall 51, as indicated in Figs. 13, 15 and 16, may be varied, to withstand the imposed stresses and strains incidental in the support of the roof membrane and associated roofing materials under varying weather conditions, and depending upon the configurations of the peripheral wall, its manner of lodgement within the ground or other support, and other concerned factors. Thus in Figs. 13, 15 and 16, the peripheral wall indicated as of concrete may have variant general quadrilateral configurations, and its upper face preferably arched to provide a substantially smooth rounded surface against which the roof membrane is brought in its varying positional relationship therewith incident to varied increase of internal atmospheric pressure. In Fig. 13, the peripheral wall is shown shored interiorly by ground lodged thereagainst interiorly of the building structure for a height above the floor level 53. Fig. 13 also illustrates the peripheral wall countershored by ground lodged exteriorly against the peripheral wall 51. In Fig. 16, the peripheral wall 51 has a cross-sectional configuration generally that of a parallelogram and having a height greater than its thickness; also shored interiorly to a height greater than that indicated in Fig. 13 as well as countershored for full height exteriorly, as indicated at 52b.

In Fig. 15, the roof membrane is shown anchored to a concrete peripheral wall 51, generally similar as in Figs. 13 and 16; however, in Fig. 15, the roof membrane is illustrated as provided with supplementary anchoring means such as guy wires 66 which may be distributed about the building structure, each guy wire being connected at one end rigidly to the peripheral wall 51 and its opposite end anchored in the ground as indicated at 67 by means of earth anchors 68.

As one manner of constructing a building embodying the invention, the procedure may be as follows, it being understood that the cited specific steps may be varied, as is apparent, to attain the objects and purposes of the invention.

As indicated in Fig. 12, assuming the structure to be erected on earth, the ground denoted generally 70, is substantially leveled at its upper surface 71, upon which are laid, see also Fig. 4, lengths of sheets 72 of the roof membrane 61, say steel sheets. The lateral edges of these sheets are welded continuously, as by electric seam-welding, soldering or the like.

About such leveled surface 71 of the earth, trenches are dug for reception of the material of the peripheral wall 51, say, of concrete, shaped and dimensioned by suitable forms, pursuant to conventional practice.

The sheets are then cut for proper lengths to provide the peripheral edges which are anchored relative to the peripheral wall, as hereinabove indicated. Assuming the air blowers to be located exteriorly of the building structure, trenches are dug exteriorly of the peripheral wall for locating suitable housings for such air blower stations. Desirably, these air blower stations are

spaced about the peripheral wall. Openings are provided in or under the peripheral wall communicating with such air blower stations. Leading from such wall openings, tunnels are dug interiorly of the leveled ground and at a level or levels appropriately below the desired level of the floor, for the reception therein of the air inflowing ducts. Passages are dug at intervals leading from such tunnels to the level of such leveled ground. Additional openings through the peripheral wall, at desired locations, are also provided for the entry and exit of personnel, trucks, airplanes, etc., depending upon the utilization of the building.

Upon installation of the air blowers, air under compression may then be supplied under the roof membrane, thus elevating the same relative to the leveled ground. In Fig. 12, elevation of the roof membrane is indicated by comparison of the roof membrane in elevated position, denoted at 12a in dot-and-dash outline, with its flat position, denoted 12 in full outline.

As indicated by Fig. 12 and disclosed generally hereinabove, advantages are attained pursuant to my invention by limiting the elevation of the roof membrane to the configuration of a shallow dome. In the instance of an embodiment of the invention of substantially circular form of the order of 1200 ft. in diameter and a vertical height of the center of the dome of the order of 60 ft. above a plane passing through the peripheral anchorage of the roof membrane, referred to hereinabove, the ratio of such vertical height of the dome to the diameter of the peripheral wall is approximately 1 to 20.

The average stretch of annealed low-carbon steel for the indicated increase of air pressure is about one percent, which is sufficiently above the yield point to insure a permanent deformation of the roof into a smooth dome of low vertical central rise. Figs. 1, 7, 12, 13 and 15 indicate generally a range of dome configuration contemplated by the invention. Steel has a maximum elongation of about twenty percent; hence there is provided an ample factor of safety for variant heights of shallow dome formations.

Upon attaining sufficient elevation, the remainder of the ground above the desired floor level is then removed. The flooring, including the discharge openings of the air inflowing ducts, may now be completed. The desired air exhaust towers may also be erected at this stage, including the air outgoing ducts leading therefrom.

A preferred form of air delivering duct systems including floor discharge openings is illustrated generally in Figs. 8, 9 and 10; as shown, such system includes mutually spaced air distribution ducts which extend through the floor.

Assuming the air blowers or compressors to be located exteriorly of the peripheral wall, as is indicated in Fig. 6, the main air inflowing ducts 55 may be arranged to be respectively connected to parallelly arranged air blowers 56, 56, driven, say, by an electric motor, indicated at 75. Such air blowers may be driven by gasoline or other explosive engines, a preferred, or alternatively by employing such gasoline engines as stand-by sources of power, in the event of failure of electrical power. Each of such main air inflowing ducts 55 may be connected with a series of distribution ducts 57 as in the manner indicated in Fig. 8. As indicated in Figs. 9 and 10, the control of the extent of diversion of the inflowing air conveyed through any distribution duct 57 to and through any individual floor or other out-

let 58 may be effected by means of a baffle 76, shown pivoted at one end and regulated as to its angle of diversion by means of an adjusting rod 77 provided with a hand-knob 78, or equivalent. Such dual air blower stations are denoted 74 in the drawings, shown distributed about the periphery of the peripheral wall 51.

Fig. 5 indicates an approved arrangement of air blowers 56, 56 combined with an air-turbine 61 motor 84 and associated main and auxiliary driving means, assembled in a single station, denoted 73; these stations may be distributed about the peripheral wall 51. In such arrangement, the blowers 56, 56 supply compressed air through the air ducts 55, 55; such air blowers may be driven directly by electric motors, indicated at 79, 79 and/or by internal combustion engines, which latter may serve as stand-by power sources. 60 represents the duct conveying air exhausted from the interior of the building structure, under pressure in excess of that of the outer atmosphere, and such air under increased pressure may be passed through the indicated air turbine 61 operating as a motor, the shaft of which may be suitably geared relative to the respective shafts of the associated air blowers 56, 56, usually by the intermediation of ratchet clutches, whereby the power imparted by the exhaust air to the shaft of the turbine motor 61 is effective as increments to and/or the drive of the air motors 56, 56 jointly or singly.

Means of entry and exit for personnel, trucks, railroad trains, etc., and for the products of manufacture, such as tanks, airplanes, etc., for which the structure has definite utility attributes, may be provided as preferred. In Figs. 1, 2, 3 and 4, there is indicated a combination entry and exit for personnel in the form of three revolving doors denoted generally 80; also a set of doors 81, 82, operable as canal lock gates as for trucks, tanks and like vehicles. Such unitary arrangement of station of entry and exit may be provided in number about the periphery of the peripheral wall 51, as desired; one such station is indicated at 83 in Figs. 1, 2 and 4. All doors or openings have alternate closing means in case of failure, such as is indicated at 80a, for the set of revolving doors 80.

Treatment of the roof in addition to the primary roof membrane may be carried as preferred.

Desirably the membrane 50 is protected by outer weather-resisting surfaces, also for thermal insulation, and particularly with a light and heat reflecting surface applied on the inward surface of the roof membrane. Typical of such additive attributes, I have illustrated in Fig. 17 the roof membrane 61, say of sheet steel, a reflecting surface of aluminum, sprayed or in the form of foil, may be applied upon its inner face, indicated at 85. Upon the exterior of the roof membrane 61, there is indicated a thickness 86 of insulation such as conventional insulation board, which may be applied in the form of layers, sheets or the like, which may be connected to one another at their lateral edges, for additional strength or to form the primary membrane. Also, an outermost layer of roofing material such as asphalt or the like, indicated at 87, or asphalt or other approved roofing sheet material, may be employed.

Fig. 18 illustrates a composite roofing of which 85 is the interior surface which may be of heat and light reflecting material such as sprayed metal, aluminum foil, etc. or may be the surface of the primary membrane 61 which might be of

sheet aluminum, stainless steel, etc. or even a bright tinned or galvanized surface of steel.

61 represents the primary membrane whose function is to confine the air within the enclosure and to take the loads of excess pressure of wind, snow and other loads. It may be of thin, high strength material such as steel, aluminum, vulcanized fibre, etc. or it may be of relatively weaker but thicker material such as compressed laminated paper board, and such building trade materials known as "Homosote" "Celotex," "Manosite," etc., or plastics such as cellulose acetate, methyl methacrylate, etc.

Preferably, such material 61 should contain entrapped air for heat insulation. It may be of a relatively ductile material or formable so that the pressure within the dome may be reduced after elevation, or it may be of a more elastic material in order to permit collapsing the roof or vary the volume, as when used as a storage tank or energy source.

87 represents the exterior surface which may be the weather-resistant surface of the primary membrane, or a coat of paint or other protective surface, or built-up felt roofing.

Fig. 19 represents a composite roofing including a similar type of membrane as in Fig. 17 or Fig. 18 showing a method of sound proofing the under surface. 87 represents the roofing surface, 86 the insulating material, 61 the primary membrane which is substantially impermeable to air and moisture vapor in the air. 88 represents a sound absorbing material of sprayed felting flock, applied blanket insulation, etc., 85 represents the reflecting inner surface which in this case is pervious to permit sound penetration into the sound absorbing material 88. The reflecting surface 85 may be sprayed metal on the sound absorbing material 88 or a perforated foil applied to the exposed surface of the sound absorbing material.

Flooring for the surfacing of the ground may be selected as preferred. Usually, concrete or the like is applicable for a large proportion of industrial uses.

If desired, exhaust openings may be located in proximity of the zones of operation of the operators, particularly for operations giving rise to fumes or other obnoxious gases.

Lighting of the enclosure is readily afforded by floor stands advantageously of the portable types, the efficiency of which is increased by the reflecting surface of the roof, above described.

This type of construction is adaptable to a means of generating power from sunlight. A preferred method is to make the primary membrane of a high strength plastic with low modulus of elasticity, say 300,000 pounds per square inch or less, transparent to solar radiation, of say .01 mu to 4.0 mu wavelength but opaque to low temperature heat radiation of say 4.0 mu to 20 mu wave lengths. It is desirable by means of laminations separated by small disks of material or by other means to form entrapped air spaces to thus increase the heat insulation of the membrane and reduce heat loss by conduction through it. The remainder of the construction is the same as described hereinabove with air blowers introducing air and air turbines extracting power from the air exhausted to pump in fresh air and further as a source of useful work such as running electric generating equipment.

Energy of sunlight will penetrate the membrane, and be transformed into heat on striking the floor of the structure. This heat will be

stored in the ground and will be transferred to the air in the enclosure of the structure.

Heating the air will tend to increase its pressure or its volume or both. This increase in quantity or pressure of air exhausted over that introduced provides the energy source from which power may be derived.

Air may be introduced continuously at floor level and withdrawn at higher temperature and 10 column continuously from the higher temperature zone near the roof, or it may be introduced intermittently say at lower temperature at night and discharged at higher temperatures during the day, thus taking advantage of the daily 15 temperature cycle. It may also be introduced at high barometric pressure and discharged at low barometric pressure, thus taking advantage of barometric variations.

Since this system is a means of collecting low 20 grade power, the efficiency may be improved by using auxiliary means of collecting energy from the sunlight such as solar heating boilers, cultivating vegetation within the enclosure. Heat energy wasted in the conventional operation of 25 solar heating boilers, cultivation of vegetation, etc., is utilized by my invention.

When used, say as a factory, waste heat from 30 lights, machinery, and occupants of the dome will also provide useful air expansion and tendency to increase the efficiency of operation of the ventilating equipment, if not actually providing excess power.

If preferred, as is indicated at 90 in Fig. 7, a 35 thermal exchanger may be employed for heating or cooling the supplied inflowing air. Such thermal exchanger may be associated with suitable air filtering means, scrubber or the like for the removal of dust or other foreign material.

Generally speaking, for maintaining relatively 40 low pressure within the enclosure of the building structure, the blowers are operated at relatively low speed. It is advantageous to employ air blowers driven by a two speed electric motor, and arranged, say as pairs, for supplying air at 45 relatively low pressure, both blowers may be concurrently operated, and when it is desired to supply air at relatively higher pressures, but one blower may be operated, at its higher speed, the other blower being shut off and its delivery opening blocked by suitable means.

It will be observed that the baffles 76 are so arranged in angularity within their respective distribution ducts 57 whereby in the circumstance of supply of inflowing air to any distribution duct from one inlet only, i. e., from one main duct only, uniformity of distribution of the air through the floor outlets 58 is nevertheless attained, namely, by the angularity of such baffles 76 which are disposed more closely to such main duct, setting up eddy currents which tend to retard flow through such more closely disposed outlets. Whereas the baffles of the more remote outlets enhance the air flow through their associated floor outlets.

Embodiments of the invention are particularly 65 advantageous as structures for the manufacture or assembly of airplanes, military tanks, large ordnance, etc., in that the enclosure of the structure is substantially free of columns and other structural supports, impeding or limiting free 70 expanse of utilization of the full square-foot-age of the floor space.

Whereas I have described my invention by reference to specific forms thereof, it will be understood that many changes and modifications

may be made provided they do not depart from the scope of the claims.

I claim:

1. A building structure comprising a vertically extending relatively rigid peripheral support, a membrane of substantially impermeable ductile metallic material serving as a primary roof element shaped at its periphery to conform to that of said peripheral support, means for anchoring the periphery of said membrane with respect to said peripheral support, means for creating within the enclosure formed by said peripheral support and said membrane and the floor or bottom surface increase of pressure of the air within such enclosure to thereby support said membrane in raised position, thereby engendering within said roof membrane tensile stresses in all directions substantially parallel to the surface of said roof membrane, and heat reflecting means carried by said roof membrane internally of the enclosure of the building structure.

2. A building structure comprising a vertically extending relatively rigid peripheral support, a membrane of substantially impermeable ductile metallic material serving as a primary roof element shaped at its periphery to conform to that of said peripheral support, means for anchoring the periphery of said membrane with respect to said peripheral support, means for creating within the enclosure formed by said peripheral support and said membrane and the floor or bottom surface increase of pressure of the air within such enclosure to thereby support said membrane in raised position, thereby engendering within said roof membrane tensile stresses in all directions substantially parallel to the surface of said roof membrane, and light reflecting means carried by said roof membrane internally of the enclosure of the building structure.

3. A building structure comprising a vertically extending relatively rigid peripheral support, a membrane of substantially impermeable ductile metallic material serving as a primary roof element shaped at its periphery to conform to that of said peripheral support, means for anchoring the periphery of said membrane with respect to said peripheral support, means for creating within the enclosure formed by said peripheral support and said membrane and the floor or bottom surface increase of pressure of the air within such enclosure to thereby support said membrane in raised position, thereby engendering within said roof membrane tensile stresses in all directions substantially parallel to the surface of said roof membrane, and heat and light reflecting means carried by said roof membrane internally of the enclosure of the building structure.

4. The method of constructing a building structure provided with a roof supported by relatively increased internal pressure which comprises employing ductile material as the primary material of the roof and subjecting such roof material to relatively increased pressure internally of the building structure to thereby stretch such roof material to its desired final configuration by the action of such increased internal pressure, thereby engendering within said roof material tensile stresses in all directions substantially parallel to the surface of said roof material.

5. A building structure comprising a vertically extending fixed peripheral support; a roof membrane of substantially impermeable ductile material shaped at its periphery to conform to that of said peripheral support; means for anchoring substantially the entire periphery of said roof

membrane with respect to said peripheral support; and means for creating within the enclosure of the building structure increase of pressure of the atmosphere therein to thereby support said roof membrane and engender within said roof membrane tensile stresses in all directions substantially parallel to the surface of said roof membrane.

6. A building structure comprising a vertically extending fixed peripheral support; a roof membrane of substantially impermeable ductile material shaped at its periphery to conform to that of said peripheral support; means for anchoring substantially the entire periphery of said roof membrane with respect to said peripheral support; and means for creating within the enclosure of the building structure increase of pressure of the atmosphere therein to thereby elevate and support said roof membrane and engender within said roof membrane tensile stresses in all directions substantially parallel to the surface of said membrane.

7. A building structure comprising a vertically extending fixed peripheral support; a roof membrane of substantially impermeable ductile material shaped at its periphery to conform to that of said peripheral support; means for anchoring substantially the entire periphery of said roof membrane with respect to said peripheral support; and means for creating within the enclosure of the building structure increase of pressure of the atmosphere therein to thereby elevate and stretch said roof membrane beyond the elastic limit and support said roof membrane and engender within said roof membrane tensile stresses in all directions substantially parallel to the surface of said roof membrane.

8. A building structure comprising a vertically extending fixed peripheral support, a roof membrane of substantially impermeable ductile material shaped at its periphery to conform to that of said peripheral support; means for anchoring substantially the entire periphery of said roof membrane with respect to said peripheral support, and means for creating within the enclosure of the building structure increase of pressure of the atmosphere therein to thereby elevate and smooth-out unevennesses in said roof membrane and engender within said roof membrane tensile stresses in all directions substantially parallel to the surface of said roof membrane.

9. The method of erecting a building structure provided with a roof supported by relatively increased internal atmospheric pressure, which comprises providing a vertically extending fixed peripheral anchorage; providing a membrane of substantially impermeable ductile material shaped at its periphery to conform to that of the peripheral anchorage; securing the peripheral edge of such roof membrane to such peripheral anchorage; and supplying increased atmospheric pressure within the enclosure of the building structure to support the thus secured roof membrane and engender within said roof membrane tensile stresses in all directions substantially parallel to the surface of said roof membrane.

10. The method of erecting a building structure provided with a roof supported by a relatively increased internal atmospheric pressure, which comprises providing a vertically extending relatively fixed peripheral anchorage; providing sheets of substantially impermeable ductile material; connecting such sheets to one another to form a substantially impermeable roof membrane; shaping the periphery of the thus formed

roof membrane to the periphery of such peripheral anchorage; securing the peripheral edge of such roof membrane to such peripheral anchorage; and supplying increased atmospheric pressure within the enclosure of the building structure to elevate and support the thus secured roof membrane and engender within said roof membrane tensile stresses in all directions substantially parallel to the surface of said roof membrane.

11. The method of erecting a building structure provided with a roof supported by relatively increased internal atmospheric pressure, which comprises providing a vertically extending fixed peripheral anchorage; providing a membrane of substantially impermeable ductile material shaped at its periphery to conform to that of the peripheral anchorage; securing the peripheral edge of such roof membrane to such peripheral anchorage; and supplying increased atmospheric pressure within the enclosure of the building structure to elevate and stretch such roof membrane beyond the elastic limit and support the thus secured roof membrane and engender within said roof membrane tensile stresses in all directions

substantially parallel to the surface of said roof membrane.

12. The method of erecting a building structure provided with a roof supported by a relatively increased internal atmospheric pressure, which comprises providing a vertically extending relatively fixed peripheral anchorage; providing sheets of substantially impermeable ductile material; connecting such sheets to one another to form a substantially impermeable roof membrane; shaping the periphery of the thus formed roof membrane to the periphery of such peripheral anchorage; securing the peripheral edge of such roof membrane to such peripheral anchorage; and supplying increased atmospheric pressure within the enclosure of the building structure to elevate and smooth-out unevennesses in the roof membrane and support the thus secured roof membrane and engender within said roof membrane tensile stresses in all directions substantially parallel to the surface of said roof membrane.

HERBERT H. STEVENS, JR.
